UNITED STATES PATENT OFFICE

142,047

DESIGN FOR A FORTY YEAR CALENDAR FRAME

Paul N. Tinello, Canastota, N. Y., assignor of
fifty per cent to Anthony Capparelli, Canastota,
N. Y.

Application February 27, 1945, Serial No. 118,169

Term of patent 14 years

(Cl. D74—5)

To all whom it may concern:

Be it known that I, Paul N. Tinello, a citizen
of the United States, residing at Canastota, in the
county of Madison and State of New York, have
invented a new, original, and ornamental Design
for a Forty Year Calendar Frame, of which the
following is a specification, reference being had to
the accompanying drawing, forming part thereof.

Figure 1 is a front elevational view of a forty
year calendar frame, showing my new design,

Figure 2 is a rear elevational view, and

Figure 3 is a side elevational view thereof.

I claim:

The ornamental design for a forty year calendar
frame, as shown.

PAUL N. TINELLO.
